STOCKING

Edward C. Hinchliff, Rockford, Ill., assignor to
Burson Knitting Company, Rockford, Ill.

Original application November 14, 1933, Serial No.
697,951. Divided and this application April 17,
1939, Serial No. 268,179

12 Claims. (Cl. 66—172)

The present application relates to a knitted stocking having an improved top fabric. This application is a division of my co-pending application, Serial Number 697,951, filed November 5 14, 1933.

The principal object of the invention resides in the production of a knitted stocking having a top consisting of a fabric of a predetermined width for attaching a garter fastener thereto 10 and possessing one-way stretch, and a strain-absorbing fabric integral with the garter attaching fabric and having two-way stretch, whereby the garter attaching fabric may have a high degree of stretch circumferentially of the stocking 15 to enable the top to be easily drawn over the knee of the wearer, and the strain-absorbing fabric may have a high degree of elastic stretch both longitudinally and circumferentially of the stocking to take up the strains of the knee fabric 20 and the garter attaching fabric of the stocking in the use thereof.

Another object of the invention resides in the positioning above the knee portion of the stocking of a strain-absorbing fabric consisting of an alternating arrangement of elastic and inelastic yarns so engaged with each other that the elastic 25 yarn may be subjected to longitudinal and lateral stretch to provide the fabric with two-way elastic stretch.

Another object of the invention resides in the provision of a weft knitted stocking having a top consisting of a garter attaching fabric weft knitted of inelastic yarn, and a strain-absorbing fabric connected thereto and knitted of elastic and 30 inelastic yarns, and possessing a high degree of elastic stretch circumferentially of the stocking and a high degree of elastic stretch longitudinally of the stocking.

A feature of the invention resides in the fabrication of the strain-absorbing fabric of an alternating arrangement of elastic and inelastic yarns so as to possess two-way elastic stretch, and will be more easily stretchable than the remaining 35 portions of the stocking attached thereto and, further, will more nearly resemble the stocking leg fabric in appearance.

With these and other objects in view, the invention will be better understood from the following detailed description taken in conjunction with the accompanying drawing, wherein:

Figure 1 is a side elevation of a stocking constructed in accordance with my invention;

Figure 2 is a side elevation of a stocking constructed in accordance with a modification of my invention;

Figure 3 is an enlarged detailed view of a portion of the stocking top showing an alternating arrangement of elastic and inelastic yarns interconnected at spaced points to provide two-way elastic stretch;

Figure 4 is an enlarged detailed view of a portion of the leg fabric.

Previous to my invention, stockings had a top fabricated entirely of inelastic yarns which had stretch in one direction only, that is to say, circumferentially of the stocking. Further, the knee portion, as well as the garter attaching portion, of the stocking were subjected to destructive strains which quite often ruptured the 10 yarn in the knee portion and the garter attaching 15 portion, causing the creation of "runs".

According to my invention, I have overcome this objectionable feature by incorporating, in the top of the stocking, elastic yarn fine in character (such as the elastic yarn shown and described in the Adamson Patent No. 1,822,847), such elastic yarn consisting of a core of elastic material covered by a fibrous yarn, such as silk or cotton. This type of elastic yarn can be effectively used with the present-day types of knitting 20 machines and, further, has a high degree of stretch in a longitudinal direction and in a transversal direction. Therefore, when such yarn is knitted into courses of plain loops in a knitted stocking top, in an alternating arrangement with 25 inelastic yarn, the top has a high degree of elastic stretch both circumferentially and longitudinally of the stocking, as compared with a stocking top fabricated entirely of inelastic yarn.

I have also discovered that when elastic and 30 inelastic yarns are arranged in alternating relationship with each other in the top of the stocking the top is more easily stretchable than when it is fabricated entirely from elastic yarn, or 35 fabricated entirely from inelastic yarn and, further, a top fabricated from an alternating arrangement of elastic and inelastic yarns more 40 nearly resembles the remaining portion of the stocking in appearance.

Referring to Figure 1, the stocking illustrated 45 comprises a top 1, a leg fabric 2, an instep fabric 3, a sole fabric 4, a heel fabric 5, and a toe fabric 6, all of which are weft knitted, the leg fabric 2 being knitted of two yarns 7 and 8, to give a better appearance to the stocking, as disclosed in 50 my parent application, Serial Number 697,951. In using my invention in the production of surgical stockings, the two yarns 7 and 8 are elastic so as to provide the necessary high degree of pressure against the leg of the wearer. As the 55

leg fabric is knitted entirely of elastic yarns, the stress-absorbing fabric 10, due to the alternating arrangement of elastic and inelastic yarns, is more easily stretchable than the leg fabric so as to absorb the strains created in the garter attaching fabric 9 and the leg fabric 2 in the use of the stocking.

The top 1 consists of a weft knitted fabric 9 of a predetermined width to enable a garter fastener to be attached thereto. As this fabric is knit of inelastic yarn, it has stretch only in one direction, that is, circumferentially of the stocking. The top further consists of a strain-absorbing fabric 14 connected to, or integral with, the garter attaching fabric and located therebelow and above the knee portion of the stocking, and fabricated from an alternating arrangement of elastic and inelastic yarns 11 and 12, as shown in Figure 3. These yarns are interengaged with each other so that the elastic yarn will stretch laterally and longitudinally in the use of the stocking, so as to provide the strain-absorbing fabric with elastic stretch both circumferentially and longitudinally of the stocking to absorb the stresses created by the pressure of the knee when flexed against the leg of the stocking and relieve the knee portion and the garter-attaching fabric of excessive strains.

In relation to Figure 2, I have illustrated the garter attaching fabric 13, as well as the strain-absorbing fabric 14 both fabricated from an alternating arrangement of interconnected elastic and inelastic yarns, so that both the garter attaching fabric and the strain-absorbing fabric 35 may have simultaneous elastic stretch both longitudinally and circumferentially of the stocking.

I wish it to be understood that the strain-absorbing fabric, consisting of an alternating arrangement of elastic and inelastic yarns, may be arranged in various positions in the stocking top above the knee of the wearer, as shown in Figures 1 and 2 of the drawing, and in Figure 1 of my co-pending application, Serial Number 697,951.

In practice, the elastic and inelastic yarns may be effectively knit into the stocking through the use of the Burson type of knitting machine wherein are incorporated two banks of needles co-functioning with two sets of yarn carriers, one feeding the elastic yarn, and the other feeding the inelastic yarn.

Subsequent to the filing of my parent application, Serial Number 697,951, I was aware that stockings had been knitted with tops fabricated from elastic and inelastic yarns, but attention is called to the fact that in such constructions, the elastic yarns were so laid in the stocking tops that they were capable of only longitudinal stretch and thus the tops possessed elastic stretch only circumferentially of the stocking, and not longitudinally of the stocking.

I am now aware of the fact that, previous to my invention, a number of succeeding courses of elastic yarn had been knitted in the top of a stocking to provide a garter effect circumferentially of the stocking, but such a construction was not practical due to the difficulty of stretching the band of elastic yarn, the difficulties experienced in knitting a number of succeeding courses of elastic yarn with the present-day types 70 of knitting machines, and the difficulties experienced due to the distortion of the fabric of the stocking that is connected to the band of elastic yarn. Further, there was too sharp a contrast between the band knitted entirely of elastic yarn 75 and the connecting fabrics of the stocking, there-

by detracting from the appearance of the stocking.

The foregoing difficulties are overcome by my invention due to the alternating arrangement of interconnecting courses of elastic and inelastic 5 yarns.

Attention is called to the fact that when elastic yarns are only laid in with the inelastic yarns, the elastic yarns can be stretched only in one direction, that is, longitudinally. In other words, 10 the elastic and inelastic yarns must be interconnected together, such as shown in Figure 3, so that when the strain-absorbing fabric is pulled longitudinally, the lengths of elastic yarn will be subjected to a lateral stretch, and when the 15 strain-absorbing fabric is pulled circumferentially, the lengths of elastic yarn will be subjected to a longitudinal stretch.

My invention is a radical improvement over what has heretofore been accomplished in the art in that I provide a stocking incorporating a novel combination of fabrics, consisting of a garter attaching fabric having only one-way stretch circumferentially of the stocking, a strain-absorbing fabric connected to, or integral with, 20 the garter attaching fabric, and fabricated from an alternating arrangement of elastic and inelastic yarns so as to be stretchable in two directions—circumferentially and longitudinally 25 of the stocking, and more easily stretchable longitudinally of the stocking than the garter attaching fabric and the leg fabric, so as to absorb the strains created in the use of the stocking.

What I claim is:

1. A stocking having a welt fabric, and a stress-absorbing section connected thereto and located above the knee, the adjacent portion of the leg of the stocking down to and below the knee being knitted to provide less easily stretchable fabric, the stress-absorbing section being knitted in- 40 integral therewith and comprising a plurality of courses of covered elastic yarn alternated with courses of inelastic yarn, whereby to provide more easily stretchable fabric to absorb the stress created when the knee is bent and, accordingly, 45 relieve the fabric in the region of the knee of destructive strain.

2. A stocking having a welt fabric, and a stress-absorbing section connected thereto and located above the knee, the adjacent portion of the leg of the stocking down to and below the knee being knitted to provide less easily stretchable fabric, the stress-absorbing section being connected therewith and comprising a plurality of courses of covered elastic yarn alternated with courses of 55 inelastic yarn, whereby to provide more easily stretchable fabric to absorb the stress created when the knee is bent and, accordingly, relieve the fabric in the region of the knee of destructive strain.

3. A stocking having a welt fabric, and a stress-absorbing section connected thereto and located above the knee, the adjacent portion of the leg of the stocking down to and below the knee being knitted to provide less easily stretchable fabric, 65 the stress-absorbing section being connected therewith and comprising a plurality of courses of relatively inelastic yarn alternating with courses of covered elastic yarn of substantially the same gauge as the inelastic yarn, whereby to provide more easily stretchable fabric to absorb the stress created when the knee is bent and, accordingly, relieve the fabric in the region of the knee of destructive strain.

4. A stocking having a strain absorbing zone 75

below the welt and above the knee, the adjacent portion of the welt being knit from relatively inelastic yarn, said strain absorbing zone being integrally knit with said welt and comprising a plurality of narrow bands constituted alternately by courses of elastic rubber thread and courses of relatively inelastic thread, whereby the stress created by the pressure of the knee when flexed against the leg of the stocking is referred to the strain absorbing zone to relieve the knee portion and the welt portion of the stocking of excessive strains.

5. A stocking having a strain absorbing weft knitted zone below the welt and above the knee, the adjacent portion of the welt fabric and the adjacent portion of the leg fabric of the stocking being weft knitted, said strain absorbing zone being integrally knit with said welt and leg fabrics of the stocking and comprising a plurality of narrow bands constituted alternately by courses of elastic rubber thread and courses of inelastic thread of a gauge approximately the same, whereby the stress created by the pressure of the knee when flexed against the leg fabric, 10 and garter strains of the welt, are referred to said strain absorbing zone.

6. A stocking having a welt fabric, and a stress-absorbing fabric connected thereto and located above the knee, the adjacent portion of the leg 15 30 of the stocking down to and below the knee being knit to provide a fabric less easily stretchable than the stress-absorbing fabric, the stress-absorbing fabric being fabricated of an alternating arrangement of elastic and inelastic yarns so interengaged with each other that the elastic yarn may be stretched longitudinally and laterally, whereby said fabric may be more easily stretchable in two directions than the leg fabric of the stocking, to absorb the stresses created when the knee is 35 40 bent and, accordingly, relieve the stocking fabric in the region of the knee of destructive strains.

7. A stocking extending above the knee and having a top consisting of a fabric of predetermined width for enabling a garter fastener to be attached thereto, and having one-way stretch circumferentially of the stocking, and a strain-absorbing fabric integral therewith and located below said garter attaching fabric and above the knee, and fabricated of an alternating arrangement of elastic and inelastic yarns so interengaged with each other that the elastic yarns may be stretched longitudinally and laterally, whereby said strain-absorbing fabric will have an elastic stretch circumferentially of the stocking and an elastic stretch longitudinally of the stocking to absorb the stresses created by the pressure of the knee when flexed against the leg of the stocking, to relieve the knee portion of the stocking and said garter attaching fabric of excessive 55 strains.

8. A stocking extending above the knee and having a knitted top consisting of a knitted fabric of predetermined width for enabling a garter fastener to be attached thereto, and having one way stretch circumferentially of the stocking,

and a knitted strain-absorbing fabric integral therewith and located below said garter attaching fabric and above the knee, and fabricated of an alternating arrangement of a multiplicity of lengths of elastic and inelastic yarns interconnected to each other at spaced points so that the elastic yarns may be stretched both longitudinally and laterally, whereby said strain-absorbing fabric will have an elastic stretch circumferentially of the stocking, and an elastic stretch longitudinally of the stocking, to take up the stresses created in the knee portion and the garter attaching fabric in the use of the stocking.

9. A stocking including a knitted garter attaching fabric, a knitted leg fabric, and a knitted strain-absorbing fabric located above the knee portion of the stocking and connected to the leg fabric and to the garter attaching fabric, and consisting of a plurality of narrow bands constituted alternately by courses of elastic rubber yarn 15 20 and courses of relatively inelastic yarn, whereby the stresses created by the pressure of the knee against the leg of the stocking are absorbed by the strain-absorbing fabric, and the stresses to which the garter attaching fabric is subjected are absorbed by said strain-absorbing fabric.

10. A knitted stocking having a top fabric knitted of inelastic yarn and a strain-absorbing fabric connected thereto and arranged in a position above the knee portion of the stocking and 30 consisting of an alternating arrangement of a multiplicity of courses of elastic and inelastic yarns interconnected together positively at spaced points, whereby the strain-absorbing fabric has two-way stretch longitudinally and circumferentially of the stocking to relieve the top fabric of excessive strains in the bending of the knee portion of the stocking.

11. A stocking including a knitted garter attaching fabric having one-way stretch circumferentially of the stocking, a knitted leg fabric, and an intermediate fabric connecting the garter attaching fabric and the leg fabric together, said intermediate fabric being located above the knee portion of the stocking and fabricated from an 40 45 alternating arrangement of interconnected elastic and inelastic yarns, whereby said intermediate fabric is more easily stretchable longitudinally of the stocking than the garter attaching fabric, to relieve the garter attaching fabric of excessive 50 garter strains in the use of the stocking.

12. A stocking including a knitted top fabric, a knitted leg fabric, and a knitted intermediate fabric located above the knee portion of the stocking and connecting the top fabric and the leg fabric together, said intermediate fabric being fabricated from an alternating arrangement of courses of elastic and inelastic yarns interlooped together throughout the length of the courses, whereby the elastic yarns will have two-way 55 60 stretch to provide the intermediate fabric with two-way elastic stretch both circumferentially and longitudinally of the stocking to relieve the top fabric and leg fabric of excessive strains.

EDWARD C. HINCHLIFF. 65
